UNITED STATES PATENT OFFICE.

WILLIAM CURRAN, OF LEWISTON, MAINE, ASSIGNOR OF ONE-HALF TO PATRICK F. TREMBLAY, OF LEWISTON, MAINE.

PICKER-STICK CHECK.

1,286,544.

Specification of Letters Patent.

Patented Dec. 3, 1918.

Application filed December 10, 1917. Serial No. 206,482.

To all whom it may concern:

Be it known that I, WILLIAM CURRAN, a citizen of the United States, residing at Lewiston, in the county of Androscoggin and State of Maine, have invented certain new and useful Improvements in Picker-Stick Checks; and I do declare the following to be a full, clear, and exact description of the invention, such as will enable others skilled in the art to which it appertains to make and use the same.

My invention has for its object to provide an extremely simple and inexpensive, yet a highly efficient and durable device for checking the speed of the picker sticks of a loom as said sticks near the limit of their travel; and with this general object in view, the invention resides in the novel features of construction and unique combinations of parts to be hereinafter fully described and claimed, the descriptive matter being supplemented by the accompanying drawings which form a part of this specification and in which:

Figure 1 is a top plan view of the invention showing the lay of the loom and the picker stick in dotted lines and illustrating the position of the check when said picker stick has reached the limit of its proceeding motion;

Fig. 2 is a duplicate of Fig. 1 but disclosing the position of the check when the picker stick has completed its receding movement;

Fig. 3 is a side elevation of the check;

Fig. 4 is a transverse section on the plane of the line 4—4 of Fig. 3;

Fig. 5 is a perspective view of the attaching plate; and

Fig. 6 is a plan view of the stick-checking bar.

In the drawings above briefly described, the numeral 1 designates the lay of a loom and 2 has reference to the picker stick which is forced in one direction to send the shuttle along the lay and then returns to normal, awaiting the return of said shuttle. It is the object of my invention to improve upon devices heretofore employed for slowly bringing the picker stick to a stand still and with this end in view I employ the construction described below.

A horizontal supporting plate 3 extends longitudinally of the lay 1, preferably below the latter and is provided with a vertical flange or the like 4 secured to said lay, lugs

6 being preferably formed at the angle between the plate and flange to space the former from the lay a suitable distance to admit the head of a bolt 7 which depends through the center of the plate. The ends 60 of the plate 3 are formed with a pair of braking projections 8 located on the lower side of said plate and having flat lower braking surfaces for a purpose to appear.

Spanning the gap between the projections 65 8 and contacting with the flat lower faces of such projections, is a stick checking bar 9, the center of said bar having an opening 9' through which the bolt 7 projects. A washer 11 and nut 10 are provided on the lower 70 end of bolt 7 and a sleeve 12 surrounds this bolt between the washer and bar 9, the upper end of said sleeve having an external shoulder 13 against which one end of a coiled spring 14 bears, the other end of said 75 spring being positioned against the washer 11. By this arrangement, it will be obvious that tightening of the nut 10 will place spring 14 under such tension as to hold the ends of the checking bar 9 in suitable frictional contact with the braking projections 8, thus resisting the movement of said checking bar to the required extent. Tightening of the nut also bows the bar as depicted in Fig. 3 and thus places it under tension to 80 assist in frictionally engaging the ends of said bar with the braking projections 8.

The entire device is spaced to one side of the path of the picker stick 2 and the inner edge of bar 9 is formed with opposed slowly 85 pitched cam surfaces 15 and 15', one surface being projected into the path of the stick 2 when the other is retracted as will be clear from Figs. 1 and 2. During its proceeding stroke, or rather near the completion of said 90 stroke, the picker stick contacts with the cam surface 15' and thus rocks the checking bar 9 around its pivot, such action however being resisted by the friction brakes above described, so that the stick 2 is slowly 95 brought to a standstill. Upon its receding or return motion the picker stick 2 contacts with the cam surface 15 which has been projected by rocking of the bar in the manner set forth. Contact of the stick with said 100 surface 15 rocks the bar 9 in the opposite direction against the action of the friction brakes, so that the return movement of the picker stick is checked in the same manner 105 as the forward movement.

From the foregoing, taken in connection with the accompanying drawing, it will be obvious that although my invention is of extremely simple and inexpensive nature, it will be highly efficient and durable, particular emphasis being laid upon the location of the friction brakes at the ends of the check bar 9, this location being much more advantageous than a central brake due to the fact that a comparatively small amount of friction at the ends of the bar will resist the movement of the latter more effectively than a larger amount at the center thereof.

Since probably the best results are obtained from the several specific details shown and described, these details are preferably employed, but I wish it understood that within the scope of the invention as claimed, numerous minor changes may well be made.

I claim:

1. A picker stick check comprising a bar extending longitudinally of the picker stick path and at one side thereof, said bar being pivoted centrally and having on one edge a pair of cam surfaces to be struck by the picker stick during its proceeding and receding strokes, whereby to alternately rock said bar in opposite directions and friction brakes for the ends of said bar to resist said rocking movement.

2. A picker stick check comprising a bar extending longitudinally of the picker stick path and at one side thereof, said bar having on one edge a pair of cam surfaces to be struck by the picker stick during its proceeding and receding strokes, friction braking surfaces against which the ends of said bar bear, and means at the center of said bar

for pivotally mounting it and constraining its ends to frictionally engage said braking surfaces.

3. A picker stick check comprising a supporting plate extending longitudinally of the picker stick path and at one side thereof, the ends of said plate having a pair of braking projections extending from one flat side of said plate, a stick-checking bar extending longitudinally of said plate and bearing at its ends against said projections, and means for pivoting the center of said bar to said plate and constraining the ends of the former to frictionally engage said projections, one edge of said bar having a pair of cam surfaces to be struck by the picker stick during its proceeding and receding strokes.

4. A picker stick check comprising a stick-checking bar extending longitudinally of the picker stick path and located at one side thereof, the inner edge of said bar having opposed cam surfaces to be struck by the picker stick during its proceeding and receding strokes, a pair of friction braking bodies against which the ends of said bar bear, and means for pivotally mounting the center of said bar and for bowing the latter longitudinally to place it under tension, whereby the ends of said bar are held in frictional engagement with said braking body.

In testimony whereof I have hereunto set my hand in the presence of two subscribing witnesses.

WILLIAM CURRAN.
